APPARATUS FOR MAKING WOOD-CHARCOAL.

1,137,852.

Specification of Letters Patent.

Patented May 4, 1915.

Original application filed February 25, 1910, Serial No. 545,897. Divided and this application filed July 21, 1913. Serial No. 429,383.

To all whom it may concern:

Be it known that I, LOUIS FÉLIZAT, a citizen of France, of Bouches-du-Rhône, France, have invented a new and useful Improvement 5 in Apparatus for Making Wood-Charcoal, which invention is fully set forth in the following specification.

This invention relates to improvements in apparatus for making charcoal and more 10 particularly to the production of charcoal from ground ligneous materials such as almond shells, peach or apricot kernels, olive husks, sawdust and the like and the invention has for its principal object to not only 15 produce a charcoal of superior quality, but to utilize the heat of combustion of the vaporous and gaseous products resulting in the carbonizing operation particularly for the production of steam.

20 The ordinary pile or heap process of making charcoal is lengthy and uncertain as to output and the quality of the product.

It is not unusual to burn under boilers industrial refuse such as waste products of 25 oil factories and other ligneous waste products for the purpose of raising steam. In view, however, of the extreme divisibility and slight density of such products, combined with the fact that they contain a comparatively large quantity of volatile substances, it is not practical to realize the full 30 calorific power of such waste burnt in this manner.

This application is a division of my co-pending application, Serial No. 545,897, filed February 25, 1910, which describes and claims the process herein disclosed but not claimed.

This process briefly stated consists in introducing, preferably by showering, the comminuted waste ligneous materials into a furnace heated to redness while introducing at the same time air to effect the complete combustion of the volatile products 45 which are dissociated from the waste and which ignite on coming in contact with the red hot walls of the chamber. The residue remains on the bottom of the chamber in the form of incandescent charcoal. The 50 hot gases are conducted under boilers to raise steam and thereby utilize the calorific power of the volatile products.

One constructional form of the apparatus

embodiment my improvements is illustrated in the accompanying drawings in which— 55

Figure 1 is a view partly diagrammatic and partly in section showing in combination the elements of my apparatus, and Fig. 2 is a view partly diagrammatic and partly in central vertical section through one of the furnaces.

As shown in the drawings, the furnace 2 is divided into two heating chambers 1 and 1' separated by a fire brick partition. The chambers 1, 1' open through outlets 3, 3, 65 controlled by doors 3', 3', into a flue 4 which conducts the hot products of combustion under the boiler, not shown. Each of these furnace chambers has a fire brick hearth 5 sloping toward the discharging door 6 or 6'. 70

The charging is done in the following manner: A hopper 7' into which the products to be burned are dumped directs them onto an endless distributing screw arranged before the battery of furnaces. At the 75 height of each furnace, an endless screw 9 disposed at right angles to endless screw 8 conducts the product to be charred into the ventilator conduit 9' which is provided with a fan 10 turning at eight to twelve hundred 80 revolutions per minute according to the nature of the product. From this conduit the product is projected in a shower into the upper part of the furnace chamber and falls onto every part of the bottom of the furnace. 85 The combustible as soon as it enters the furnace liberates all its volatile portion which inflames in contact with the red hot walls of the furnace and in presence of the air introduced with the combustible. The residue 90 falls to the bottom in the form of incandescent charcoal while the products of combustion are discharged through the flue 3. The hopper 7' is provided with a register 11 just above the screw 9 for the purpose of regulating the admission of the product. At the start the furnace is gradually heated up to a red heat, the residues in question are then cast in the form of a shower over the whole 95 surface of the hearth by means of a small wheel with vanes or blades fed by a helical or screw conveyer or distributor. The volatile products become dissociated and ignite on coming into contact with the red hot furnace walls and the residue remains on the 100 hearth in the form of incandescent charcoal.

105

which is protected from further combustion by the insufficient air supply. About every three hours the charcoal lying on the heath is removed through the doors 6 and 6' and thrown into a small truck 7 where it is smothered or quenched. To insure the proper working of the boiler, the furnaces 1 and 1' are emptied alternately so that one shall always be in action. By this means it is possible to utilize residues of the kind in question in a much more economical manner than heretofore so long as they are of a combustible nature. Thus for instance the whole of the volatile products without exception on coming into contact with the red hot walls of the furnaces become ignited and burn in a complete manner; moreover it is practicable by this means to burn with excellent results certain residues which are so pulverized or charged with water that it would be almost impossible to burn them on fire grates.

The residue of wood charcoal obtained by the process hereinbefore described has a commercial value superior to that of the combustible burnt. Thus, taking as an example a steam boiler burning with ordinary grates 1000 kilos of ground nut shells, for instance, worth about sixty cents, only about 800 kilos of the shells would require to be burned with the process forming the subject-matter of this application for the same quantity of water evaporated in the boiler, but besides this there would be obtained as residues 220 kilos of charcoal worth \$1.60 to

\$2.00. As the residues hereinbefore referred to yield from 22 to 28% of their weight of wood charcoal, this means of production becomes of great interest at a time when wood charcoal is becoming rarer and rarer notwithstanding its low cost price.

What is claimed is:

1. In a furnace for making charcoal from residues of ligneous materials, the combination of a carbonizing chamber, an inlet conduit opening into said chamber above the charcoal level, said conduit containing a receiving hopper and means for showering said ligneous material into said carbonizing chamber, a discharge opening located substantially opposite the inlet conduit for permitting the escape of burning gases, and an opening in the lower part of said chamber for removing the charcoal.

2. A furnace for making charcoal from residues of ligneous materials comprising a carbonizing chamber having a charging inlet above the charcoal level and a discharge opening substantially opposite said inlet, and means for showering the ligneous materials through said inlet into the zone of partial combustion in the upper part of the chamber and onto the furnace hearth.

In testimony whereof I have signed this specification in the presence of two subscribing witnesses.

LOUIS FÉLIZAT.
